UNITED STATES PATENT OFFICE.

THEODOR KIHLGREN, OF SPRINGFIELD, MASSACHUSETTS, ASSIGNOR, BY MESNE ASSIGNMENTS, TO NATIONAL EQUIPMENT COMPANY, OF SPRINGFIELD, MASSACHUSETTS, A CORPORATION OF MASSACHUSETTS.

STRINGING DEVICE FOR MAKING CONFECTIONS.

1,210,946.

Specification of Letters Patent.

Patented Jan. 2, 1917.

Application filed September 23, 1908. Serial No. 454,422.

To all whom it may concern:

Be it known that I, THEODOR KIHLGREN, a citizen of the United States of America, residing at Springfield, in the county of 5 Hampden and State of Massachusetts, have invented new and useful Improvements in Stringing Devices for Making Confections, of which the following is a specification.

My present invention relates to an improved machine for decorating candies and particularly to a machine constructed and arranged to deposit a string or ridge of a pasty material, as chocolate, either in a zig-zag, S-shaped, curved, or looped line or path, 5 upon pieces of candy or like articles as they are carried beneath the receptacle. The movement of the receptacle over the candies in a horizontal plane and at an angle to the movement of the candies under the receptacle will result in laying the string or ridge of decorating material in the same manner as if the two movements were compounded, and the resultant movement were given to the receptacle alone. Thus, if the receptacle 5 is given either a circular movement or a straight line movement across the line of movement of the candies, various decorative effects will result.

The invention broadly consists in providing a suitable receptacle for holding semi-liquid chocolate or like pasty material and having an orifice in the lower portion thereof for its escape, and mounting in the receptacle an improved agitating member as 5 more particularly set forth in the annexed claims at or near the outlet opening operable to effect the expulsion of the material in a string for decorative purposes and prevent any clogging of the outlet, and means 0 to move the receptacle in a curved and substantially horizontal path or reciprocate it in a straight substantially horizontal path, the invention being particularly characterized in the provision of said agitating member operable continuously while the receptacle moves in either path to insure the continuous expulsion of a decorating string to be laid in accordance with the movement of the receptacle. 5 A further object of the invention is to provide a machine having the aforesaid improved features of construction and ar-

ranged to lay the decorating string emitted from the outlet of the receptacle onto goods carried by a moving conveyer whereby the 55 configuration or form of the decoration depends both on the movement of the conveyer and the movement of the receptacle. A well-known machine having a conveyer for goods which may be decorated by the machine embodying the present invention is illustrated in the patent to Magniez No. 735,890, August 11, 1903, or Carlson No. 717,970, January 6, 1903.

Various specific objects of the invention 65 will be brought out in the detailed description and then defined in the claims forming a part of this specification.

This invention is designed to apply to or decorate the confections with a single line 70 only of chocolate, or other semi-liquid material, and is not intended to entirely cover or flood the confections.

Referring briefly to the drawings forming a part of this application,—Figure 1 is 75 a vertical sectional view through the axis of the rotating member. Fig. 2 is a transverse sectional view on the line 2—2, of Fig. 1. Fig. 3 is a detail perspective view showing the means for imparting axial movement to 80 the rotating member during the rotation of the same. Fig. 4 is a transverse sectional view on the line 4—4 of Fig. 1, looking in the direction of the arrow. Fig. 5 is a plan view of means for holding a series of machines and for imparting a reciprocating or circular motion thereto. Fig. 6 is a side view of the same partially in section. Figs. 7 and 8 show different forms in which the chocolate is left on the tops of the moving 90 chocolates.

Referring now in detail to the various figures of the drawing,—*a* designates the barrel portion of the receptacle for holding the liquid chocolate designated at *b*, this receptacle being provided with an arm *b*¹ for the purpose of securing the same to a suitable support as shown at *c*. A hopper or an inlet opening for the introduction of the liquid chocolate into the receptacle *a* is 100 shown at *d*. Secured to the bottom of the barrel *a* is a plate *e* that is provided with an aperture *f* in its lower portion for permitting the escape of the chocolate from the

receptacle *a*, and leading to the aperture are inclined sides *g* integral with the plate *e*.

h designates an annular chamber surrounding the barrel *a* and is for the purpose 5 of introducing steam or hot water into the space *i* for maintaining the chocolate contained in the receptacle *a* at a constant temperature, preferably about 90° F.

Extending upwardly from the barrel *a* 10 are two vertical members *j*, and a web or disk element *k*, shown in Fig. 3, which connects the upper end of these members. This web is internally threaded, as shown at *m*, for the purpose of receiving an adjustable nut *n*, the upper surface of which is provided with elevations and depressions *o* forming in effect an undulating or wavy surface, the purpose of which will be referred to shortly. The lock-nut *p* is carried 15 or mounted on the threaded portion *q* of the adjustable nut *n*, the purpose of which is to adjustably lock the nut *n* in the member *k*.

r designates a shaft provided with a screw 20 *s* thereon at its lower portion, but the diameter of which screw is less than the internal diameter of the barrel *a*. The lower portion of the rotatable shaft *r* is made conical and is also provided with grooves *v* 25 therein, and the lower portion *t* being arranged in the conical portion *g* of the plate *e*, as clearly shown. The upper portion of the shaft *r*, as shown at *w*, has mounted thereon a disk-shaped member *x* which is secured thereto by means of the set screw *y*. The under surface of this member *x* is provided with elevations *z* that are adapted to contact with the elevations and depression *o* of the member *n*, whereby when the shaft *r* 30 is rotating by means of a suitable pulley 2 and a belt 3, or any equivalent means, so that a reciprocating motion will be simultaneously imparted thereto, the two movements will cause the liquid chocolate to be forced downward through the orifice *f* in a continuous and uniform stream that will fall onto the upper surface of the creams 4 which are carried below the orifice *f* on a moving belt or conveyer 5, as shown at 6.

In order to constantly maintain the disk-shaped member *x* and the nut *n* in engagement with each other, I provide a coiled spring 8 that encircles the upper portion of the shaft *r* and is located between the member *q* and the pulley 2, and also to permit this reciprocation or vertical up and down movement of the shaft *r*, the set-screw 9 of the pulley 2 engages a groove or spline 10 in the portion *w* of the shaft.

The upper end of the barrel *a* is closed by means of a plate 11, and a pipe 12 serves as a means for supplying a suitable heating medium to the chamber *i*.

Referring briefly now to the operation of my improved chocolate stringing machine,

it being understood that the chocolate has been placed in the receptacle *a* and the shaft rotating as described: The reciprocating and rotary movement that is imparted thereto will cause the chocolate to flow in a steady and uniform stream through the aperture *f* downward onto the creams 4. The rotary movement will cause, by means of the screw *s*, to force the chocolate downward, and the reciprocating movement will serve to forcibly drive through the orifice *f*, any obstructions that may occur to impede the free flow of the chocolate, and the grooves *v* will serve the purpose of breaking up any obstruction or clogging of the orifice *f* should any occur.

In order to gage the lower end of the screw *r* with relation to the orifice *f*, the rotation of the nut *n* in the member *k* will raise or lower the screw, and the lock-nut *p* which is provided with suitable openings 13 will effectively maintain the vertical position of the rotating member.

It will therefore be seen that I have produced a very simple and efficient device for accomplishing the objects above set forth.

Referring now to the construction of the means for imparting various motions to the stream of flowing chocolate, whereby as the stream strikes the confections that are moving in a horizontal direction under the stringing machines, a wavy, zigzag or other shaped line or string of chocolate may be left thereon, depending upon the adjustment of the retaining means for the stringing machines.

15 designates in general outlines a rectangular frame or casting in which are located the shafts or spindles *r* in the bored out or recessed portion 16, as shown in dotted lines in Fig. 6. Immediately above the recesses 16 is a trough-shaped portion 17 for receiving the liquid chocolate or other semi fluid or pasty material that is to be fed downward onto the confections 4 (see Fig. 6). The drive-shaft for the series of spindles *r* is designated at 18, on the upper end of which is mounted a gear 19 which meshes with an intermediate gear 20 that in turn meshes with the gear 21 on the upper end of the first spindle *r*, and this gear, in turn, meshes with and drives the gear 22 that is mounted on the upper end of the next spindle, and so on throughout the series of spindles, as clearly shown in Figs. 5 and 6. The gears 19 and 20 are held in their positions by means of the casting or double arm construction 23 which also affords a bearing element for the upper end of the drive-shaft 18, as shown at 24.

25 designates a framework for supporting the rectangular chocolate carrying receptacle 15.

26 designates an eccentric strap piece having an opening 27 in one end thereof which

is concentric with the bolt 28 which secures the piece 26 to the rectangular frame 15.

29 designates a bolt or stud which has a screw-threaded connection with the frame 15 and passes through the opening 27 whereby the eccentric strap piece 26 may be rigidly secured to the frame 15.

30 designates an eccentric that is located in the opening 31 of the eccentric strap piece 26 and is secured to the shaft 18 by means of the pin 32. At the opposite end of the frame 15 is a second eccentric strap piece 33, and shaft 34 carrying an eccentric 35, the shafts 18 and 34 carrying an eccentric 35, the shafts 18 and 34 being geared together and therefore operating in unison. When the shafts 18 and 34 are operated the eccentrics 30 and 35 will cause the frame 15 to move in a circular path, and when the chocolate is flowing from the orifice *f*, as shown in Fig. 6, it will be deposited on the confections 4 in the manner shown in Fig. 7. The movement of the frame 15 may be varied by clamping the eccentric strap piece 26 in various positions by means of the bolt 29 and its companion bolt 36 in the piece 33.

If it is desired to deposit the stream of chocolate in the path shown in Fig. 8, it is only necessary to loosen the bolts 29 and 36 when the frame 15 will have simply a reciprocating movement imparted thereto by means of the eccentrics 30 and 35. In order to guide the frame 15 in its reciprocating movements, bars or rods 37 and 38 are placed on the frame 25 and temporarily held in place by means of the pins 39 (see Fig. 5). The opening 40 for the drive-shaft 18 in the frame 15 permits the frame to reciprocate as readily understood.

It will be observed that the belt and pulley construction shown in Figs. 1 and 2 is replaced in the above modifications by the series of gears mentioned.

It should be stated that when the bolt 29 is loosened, the yoke-shaped member simply oscillates on the stud 28. In order to permit the rectangular frame 15 to move as above described in either a straight line or in a circular path, the intermediate gear 20 travels or rolls on the gears 19 and 21, and in order to permit this rolling movement coincident with the movements of the frame 15, a second arm 42 is pivotally connected to the arm 23 by means of the pin 43 (see Fig. 6) whereby the arms 23 and 42 will move with relation to each other on the pin 43 during the movements of the frame, as readily understood.

Having explained the principle of my machine and the best mode in which I have contemplated applying that principle, what I claim, is:—

1. A chocolate stringing machine having in combination a receptacle for containing liquid chocolate, a member located therein, and means for continuously and simultane-

ously imparting a rotating and a reciprocating movement to said member, as described, the means for imparting the reciprocating movement to said member being independent of the action of the chocolate contained in the receptacle. 70

2. A chocolate stringing machine having in combination with a receptacle therefor which is provided with an opening for the delivery of the chocolate, a rotating member 75 located therein, means associated with the rotating member for imparting a reciprocating movement thereto, said means comprising a nut provided with a wavy upper surface and an element carried by the rotated member having interengaging devices for engaging the wavy surface of the nut, and means for maintaining the said surface and the devices carried by the element in contact, as described. 80

3. A machine for controlling the flow of pasty material, in combination, a receptacle having a conical-shaped opening therein, a rotatable shaft provided with a grooved end located in the opening, and means for rotating the shaft whereby clogging of the opening is prevented, and means for imparting a reciprocating movement to the shaft, said shaft having a spiral or screw mounted thereon and rotating in the pasty material, 95 whereby the material may be forced through the opening as described. 90

4. A machine for stringing pasty material having in combination a receptacle therefor provided with an outlet opening, and means 100 for imparting to the receptacle a reciprocating movement and a feed screw located in the receptacle, and continuously operable driving means to rotate the feed screw during the movement of the receptacle. 105

5. A chocolate stringing or decorating machine comprising a receptacle for containing the material, and having an outlet in the lower portion thereof, a member provided with a screw for expelling the material, and means for reciprocating the receptacle in a line transversely to the line of movement of confections to be decorated. 110

6. In a chocolate stringing machine, a receptacle for the semi-liquid chocolate having 115 a suitable discharge opening, a member located in the stream of chocolate passing through said opening, and means to impart reciprocatory movements to said member to prevent the clogging of said opening, said 120 means including a stationary member with a wavy surface, substantially as described.

7. The combination with a receptacle for containing semi-liquid pasty material having a discharge outlet orifice therein, a rotatable member provided with a screw-blade arranged in the outlet orifice of said receptacle, said rotatable member having a grooved end portion, substantially as described. 125

8. A chocolate stringing machine having 130

- in combination with a receptacle for containing said material, the receptacle having a discharge orifice, means comprising a feed-screw having grooves and located in the discharge orifice, substantially as described.
9. The combination, in a chocolate stringing machine, a receptacle having an outlet orifice, a feed-screw located in the receptacle for expelling the chocolate, means for rotating the same, an adjustable nut provided with a wavy surface, means for locking the nut, and means on the wavy surface of said nut whereby the feed-screw may be reciprocated, substantially as described.
- 10 15. 10. The combination with a liquid containing receptacle having a conical-shaped discharge orifice, expelling means for the liquid, said means having a conical-shaped end entering the orifice, and means for imparting a rotary and reciprocating movement thereto, substantially as described.
11. In a machine of the kind described, the combination with a receptacle for containing pasty material, and provided with a discharge orifice in the wall thereof, a rotary member for forcing the material through the orifice, the orifice having converging walls, and the rotary member being provided with a conically-shaped end portion and extending into the conically shaped space surrounding the orifice, substantially as described.
12. In a machine of the kind described, the combination with a receptacle for containing pasty material and provided with a discharge orifice in the wall thereof, a rotary member for forcing the material through the orifice, the orifice having converging walls, and the rotary member being provided with a conically-shaped end portion and extending into the conically shaped space surrounding the orifice, and means for reciprocating said rotary member, substantially as described.
13. In a machine of the kind described, the combination with a receptacle for containing pasty material and provided with a discharge orifice in the wall thereof, a rotary member for forcing the material through the orifice, the orifice having converging walls, and the rotary member being provided with a conically shaped end portion and extending into the conically shaped space surrounding the orifice, means for reciprocating said rotary member, and means

for imparting a reciprocating movement to the receptacle, substantially as described.

14. In a machine of the kind described, the combination with a receptacle for containing pasty material, and provided with a discharge orifice in the wall thereof, a rotary member for forcing the material through the orifice, the orifice having converging walls, and the rotary member being provided with a conically shaped end portion and extending into the conically shaped space surrounding the orifice, means for reciprocating said rotary member, and means for imparting a circular movement to the receptacle.

15. A stringing or decorating machine, comprising, a receptacle for the material and having an outlet opening in the lower portion thereof, a member arranged in the receptacle and adapted to enter said outlet opening, and means to rapidly vibrate said member through a small amplitude in said opening whereby the expulsion of a continuous string of material from said opening is insured.

16. A machine for depositing a pasty material, comprising, a receptacle for the material and having a discharge orifice with converging walls, a member to expel the material through the orifice, said member being provided with an end portion located between and approximately corresponding to the walls of said orifice, and means to rapidly vibrate said member in line with the orifice through a small amplitude, whereby the material is pinched between said member and walls and thereby expelled through the orifice in a continuous string.

17. A candy decorating machine, comprising, a frame, a receptacle for the material having a series of small orifices in the bottom portion thereof, means to agitate the material at or near said orifices, a cam arranged in the frame adjacent each end of the receptacle and means connected to the receptacle operable by said cams to move the receptacle in a curved path, said last-mentioned means being adjustable to vary the action of the cams and thus the movement of the receptacle.
